US0D1083924S

(12) **United States Design Patent** (10) Patent No.: **US D1,083,924 S**
(45) Date of Patent: ** Jul. 15, 2025

(54) **KEYBOARD**

- (71) Applicant: **Logitech Europe S.A.**, Lausanne (CH)
(72) Inventors: **Benjamin Ehrenberg**, Aschaffenburg (DE); **Irfan Shabbir Kachwalla**, Taipei (TW); **Sandipan Bhuyan**, Honk Kong (HK); **Nicholas Jinkinson**, St-Sulpice (CH)
(73) Assignee: **Logitech Europe S.A.**, Lausanne (CH)
(**) Term: **15 Years**
(21) Appl. No.: **29/908,574**
(22) Filed: **Jan. 12, 2024**

Related U.S. Application Data

- (63) Continuation of application No. 29/863,031, filed on Dec. 14, 2022, now Pat. No. Des. 1,042,459, which is a continuation of application No. 29/773,433, filed on Mar. 9, 2021, now Pat. No. Des. 976,260.

(57) **CLAIM**

The ornamental design for a keyboard as shown and described.

DESCRIPTION

FIG. 1 shows a top, front perspective view of a keyboard showing our new design;
FIG. 2 shows top, rear perspective view thereof;
FIG. 3 shows a top plan view thereof;
FIG. 4 shows a bottom plan view thereof;
FIG. 5 shows a front elevation view thereof;
FIG. 6 shows a rear elevation view thereof;
FIG. 7 shows a left-side elevation view thereof; and,
FIG. 8 shows a right-side elevation view thereof.
The broken lines depict portions of a keyboard in which the design is embodied that form no part of the claimed design.

1 Claim, 5 Drawing Sheets
